CLAIM

The ornamental design for an information terminal, as shown and described.

DESCRIPTION

FIG. 1 is a top, front, left side perspective view of an information terminal showing my new design;

FIG. 2 is a top plan view thereof;

FIG. 3 is front elevational view thereof;

FIG. 4 is a left side elevational view thereof;

FIG. 5 is a right side elevational view thereof;

FIG. 6 is a rear elevational view thereof;

FIG. 7 is a bottom plan view thereof;

FIG. 8 is a top, front, left side perspective view of a second embodiment of my design;

FIG. 9 is a top plan view thereof;

FIG. 10 is a front elevational view thereof;

FIG. 11 is a left side elevational view thereof;

FIG. 12 is a right side elevational view thereof;

FIG. 13 is a rear elevational view thereof;

FIG. 14 is a bottom plan view thereof.

In FIGS. 1 and 8 the drawer is shown in the opened position.
